US00D849231S

(12) **United States Design Patent** (10) **Patent No.:** **US D849,231 S**
(45) **Date of Patent:** **** May 21, 2019**

(54) **NEBULIZER**

(71) Applicant: **MICROBASE TECHNOLOGY CORPORATION**, Taoyuan (TW)

(72) Inventors: **Shao-Ming Yang**, Taoyuan (TW); **Chien-Hua Lin**, Taoyuan (TW); **Chih Wei Chou**, Taoyuan (TW)

(73) Assignee: **MICROBASE TECHNOLOGY CORPORATION**, Taoyuan (TW)

(**) Term: **15 Years**

(21) Appl. No.: **29/569,565**

(22) Filed: **Jun. 29, 2016**

(30) **Foreign Application Priority Data**

Jan. 26, 2016 (TW) 105300384

(51) **LOC (11) Cl.** **29-02**

(52) **U.S. Cl.**

USPC **D24/110**

(57) **CLAIM**

The ornamental design for a nebulizer, as shown and described.

DESCRIPTION

FIG. 1 is a perspective view of a nebulizer showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings depict portions of the nebulizer that form no part of the claimed design.

1 Claim, 7 Drawing Sheets
